(57) **CLAIM**

The ornamental design for a header panel with outward, convex curvature, as shown and described.

DESCRIPTION

FIG. 1 is an isometric view of a header panel with outward, convex curvature in accordance with a first embodiment of my design.

FIG. 2 is a front view thereof.

FIG. 3 is a bottom view thereof.

FIG. 4 is a top view thereof.

FIG. 5 is a right side view thereof.

FIG. 6 is a left side view thereof.

FIG. 7 is a rear view thereof.

FIG. 8 is an isometric view of a header panel with outward, convex curvature in accordance with a second embodiment of my design.

FIG. 9 is a front view thereof.

FIG. 10 is a bottom view thereof.

FIG. 11 is a top view thereof.

FIG. 12 is a right side view thereof.

FIG. 13 is a left side view thereof; and,

FIG. 14 is a rear view thereof.

The broken lines depict portions of the article that form no part of the claimed design.

1 Claim, 10 Drawing Sheets
